SMOKER'S ITEM

Goswin Droop, Habana, Cuba

Application April 16, 1934, Serial No. 720,857
In Cuba November 28, 1933

3 Claims. (Cl. 131—10)

This invention relates to improvements in a cigar, cigarette holder or pipe stem and consists in the constructions, arrangements and combinations herein described and claimed:

5 It is an object of the invention to provide a stem or holder comprising two or more complementary elements which may be quickly assembled in compact relationship, providing an air tight seal to prevent leakage between contacting surfaces, as well as providing a holder or stem which may be readily separated for the purpose of cleaning the bore thereof.

10 It is also an object of the invention to provide a holder in which the complementary elements are longitudinally slidable relatively to one another, thereby providing a novel means for disengaging a cigar or cigarette butt from the holder.

15 Additional objects, advantages and features of invention will be apparent from the following description and in conjunction with the accompanying drawing forming a part of this application, wherein

20 Figure 1 is a side elevation of a holder constructed in accordance with my invention, in use.

25 Figure 2 is a longitudinal sectional view thereof.

Figure 3 is an elevational view, similar to Figure 1, illustrating a modification.

30 Figure 4 is a cross section on the line 4—4 of Figure 3.

Figure 5 is an end elevation of Figure 1.

Figure 6 is a plan view of one of the elements constituting the holder.

35 Figure 7 is a plan view of the other of the elements, and

Figures 8 to 13 are end elevations of modified forms of the holder.

40 Referring more particularly to the drawing, the reference character 10 generally designates a holder composed of complementary sections 11 and 12. The sections 11 and 12 are of like lengths, which may vary according to desires of the manufacturer, and have an exterior appearance or contour of any usual and well known cigarette holder, providing a mouth piece 14 and cigarette receiving-end 15.

45 The sections 11 and 12 are separately molded of suitable material or otherwise formed, the contacting faces 16 of which are smooth throughout their lengths in order to insure a snug fitting relation, and each section further has at the end 15 a cylindrical recess 17 which defines a socket 18 for receiving a cigarette when

the sections are engaged, as clearly seen in Figure 2.

5 The sections 11 and 12 are adapted for interlocking engagement, separable by longitudinal movement with respect to one another, and attention is now directed to Figures 1, 2, 5, 6 and 7, wherein it will be seen that the section 11 in the present instance, comprises a channel 19, extending longitudinally of the section from the recess 17 and terminating at a point a short 10 distance from the extremity of the mouth-piece 14, where the channel is reduced as at 20. The channel 19 is undercut along its longitudinal sides, as at 21, providing a dovetailed groove 22. The section 12 has a longitudinal channel 23 15 extending from the recess 17 to the extremity of the mouth piece 14, this channel being of the same dimensions as the portion 20 of the section 11, and flush with the edges of the channel a pair of ribs 24 are formed, the outer longitudinal sides of which are mitered at an angle corresponding to the sides of the dovetailed groove 22, so that when the ribs are engaged with the grooves, the sections 11 and 12 will be 20 securely held together, bringing the face portions 16 of the sections into air-tight contacting relation.

25 It should be noted that the ribs 24 are of the same length as the grooves 21 and that the shoulder 25 formed at the junction of the channel 19 30 and reduced portion 20 forms a stop means for limiting sliding movement between the two sections, thus insuring endwise alignment between the sections.

35 With the sections 11 and 12 in engaged relation, it will be readily seen that the bottom wall of the groove 22, the portion 20 and the channel 23 define the smoke channel, and that upon separation of the sections 11 and 12, by effecting opposite longitudinal sliding movements thereto, 40 the various channels and grooves may be easily cleaned of sediment or other accumulations therein. Also, as may be seen by the dotted lines in Figure 2, the extraction of a cigarette butt may be readily effected by sliding one of the sections 45 relatively to the other. After extraction of the butt, the sections may be returned to their normal operative positions.

50 It is contemplated that the grooves and tongues will be ample for the purpose of holding the sections together, as well as preventing undue sliding movements, but if desired, the sections 11 and 12 may be provided with circumscribing grooves 26. A split ring 27 may then be slid into 55 respective grooves for further securement of the

sections. These rings or bands may also serve the function of ornamenting the holder, as may be desirable in the more expensive holders.

The holder is susceptible to numerous modifications, such as illustrated in Figures 8 to 13. In Figure 8 the section 28 is substantially in the form of a keystone, interfitting with the section 29. Each section 28 and 29 has a channel which when the sections are interfitted define a smoke channel 30.

In Figure 9, the section 31 has substantially a cross formation embodying oppositely disposed ribs 32 and the section 33 is formed with a cut-away part conforming thereto so as to receive the section 31 therein. Each section is provided with complementary channels defining the smoke duct 34.

Figure 10 illustrates a section 35, the side walls of which are angularly inclined toward each other as at 36, for a distance, and then extend abruptly away from each other where they are joined by a horizontal wall 37. It will thus be seen that the lateral angular ribs 38 are thus formed cooperable with a similarly formed passage in the section 39.

The modification shown in Figure 11 is quite similar to that shown in Figure 10, but in the present instance the walls 40 of the section 41 are parallel.

In Figure 12, I have illustrated the section 42 approximately sector-shaped, one side of which is cut to provide a pair of oppositely disposed dovetailed ribs 43, slidably received within a dovetailed groove of the section 44.

The final form illustrated in Figure 13 is quite similar to that disclosed in Figures 1 and 2, inasmuch as the sections defining the holder are medially and longitudinally divided, but in the present instance, each of the sections 45 and 46 are provided with a dovetailed groove 47, and dovetailed rib 48, the rib of one section being slidably received within the groove of the other section.

It should be understood that the grooves of the various constructions may have a slight taper, if desired, in order to further insure a tight fit between the sections, due to increased friction; or the faces 46 of the sections may have a slight curvature to produce the same results.

From the foregoing it will be apparent that I have provided a construction of extreme simplicity, and well adapted for use in the construction of holders for cigarettes and cigars, as well as pipe stems, and that the smoke dust may be

readily exposed for cleaning by a quick separation of the complementary sections.

I claim:—

1. A cigar or cigarette holder comprising a pair of complementary sections having flat abutting face portions and recesses at one end defining a socket, one of said sections having a dovetailed groove extending from its respective recess to a point intermediate the length of the section, a smoke channel in the section in alignment and communicating with the groove, the smoke channel being of less diameter than the groove, defining a shoulder at the juncture therewith, a dovetailed rib formed upon the other section, said rib being of a length corresponding to that of the groove whereby when said sections are in engaged position the rib will engage said shoulder, and a smoke duct extending medially and longitudinally of said rib and in communication with the first named smoke duct. 10

2. A cigar or cigarette holder comprising a pair of complementary interfitting sections, each of said sections having recesses at one end defining a socket, one of said sections having a groove ex- 15

tending from its respective recess to a point intermediate the length of the section, a smoke channel in the section in alignment and communicating with the groove, the smoke channel being of less diameter than the groove, defining a shoulder at the juncture therewith, a rib formed upon the other section, said rib being of a length corresponding to that of the groove whereby when said sections are in engaged position the rib will engage said shoulder, and a smoke duct extending medially and longitudinally of said rib and in communication with the first named smoke duct. 20

3. A cigar or cigarette holder comprising a pair of complementary interfitting sections, each of said sections having a recess at one end defining a 25

socket, one of said sections having a groove ex- 30

tending from its respective recess to a point intermediate the length of the section, a smoke channel in the section in alignment and communicating with the groove, the smoke channel being of less diameter than the groove, defining a shoulder at the juncture therewith, a rib formed upon the other section, said rib being of a length corresponding to that of the groove whereby when said sections are in engaged position the rib will engage said shoulder, and a smoke duct extending medially and longitudinally of said rib and in communication with the first named smoke channel. 35

4. A cigar or cigarette holder comprising a pair of complementary interfitting sections, each of said sections having a recess at one end defining a 40

socket, one of said sections having a groove, a smoke channel in the section in alignment and communicating with the groove, the smoke channel being of less diameter than the groove, defining a shoulder at the juncture therewith, a rib formed upon the other section and slidably in 45

the groove, whereby when said sections are in engaged or normal positions the rib will engage the shoulder, and a smoke channel extending medially and longitudinally of said rib and in communication with the first named smoke channel. 50

GOSWIN DROOP.
